UNITED STATES PATENT OFFICE.

JOSEPH R. WITZEL, OF PHILADELPHIA, PENNSYLVANIA,

PREPARING GERM MATTER FOR MEDICINAL USE.

SPECIFICATION forming part of Letters Patent No. 531,889, dated January 1, 1895.

Application filed November 27, 1891. Serial No. 413,221. (No model.)

To all whom it may concern:

Be it known that I, JOSEPH R. WITZEL, a citizen of the United States, residing in the city and county of Philadelphia, State of Pennsylvania, have invented a new and useful Improvement in Methods of Preparing Germ Matter for Medicinal Use, which improvement is fully set forth in the following specification and accompanying drawing.

10 My invention relates to improvements in methods of manufacturing germ medicinals, such as tubercular, typhoid or diphtheritic germs, and has for its object the reducing of the germ or germ material to a condition de-
15 void of danger for medicinal use, by produc-
ing a lifeless mass, thereby preventing any
infection therefrom without changing the ele-
mentary constituents of the said germ or germ
material, and rendering it better fit for ther-
apeutic purposes, and for this purpose it con-
sists of the method hereinafter set forth,
whereby the germ matter as taken from the
corpse, said matter being in either a solid or
a liquid condition, or partly solid and partly
25 liquid, is placed *in vacuo* and subjected to a
series of successions and dilutions for the
purpose described.

In the figure in the drawing, which repre-
sents a side view of a device or apparatus
30 suitable for carrying out my process, A design-
ates a box or other vessel suitably supported
in or on one end of the lever B, the other end
of said lever being pivoted to a standard or
frame C.

35 Projecting from one side of the lever B is a
pin D, which fits in a cam groove E in the side
of the wheel F secured to the shaft G. The
said shaft is mounted in the frame C, and is
provided with a handle H for rotating it.

40 The vessel A is adapted to inclose a vial or
other suitable vessel J, containing the germ
matter in *vacuo*, and is provided with a cap
K, which, when screwed on the body of the
vessel A, bears against the cork L of the vial
45 J, so as to keep the same in place. The vial
J is provided with a valve M for opening or
closing the mouth thereof.

In carrying out my process of preparing
the germ matter for medicinal use, the said
50 matter is placed in the vial J, which may be
of any shape, so as to occupy about one-third

of the space within the same. The air is now
withdrawn from the vial by means of an air-
exhaust pump, and the valve M in the mouth
of the vial closed. The vial J is now placed
55 in the box A, and the cap K screwed thereon,
so as to bear against the cork L, which had
been inserted in the mouth of the vial J, and
thereby hold the latter in position within the
box A, while the shaft G is rotated by means
60 of the handle H, so as to rotate the wheel F,
and thereby raise and lower the lever B, thus
imparting a series of successions to the germ
matter held *in vacuo* in the vial J. After the
germ matter has been subjected to the suc-
65 cussions for about five minutes heat is ap-
plied to the same, and the germ matter kept
at boiling point until all vitality therein is
destroyed. It is then set aside in a dark and
cool room. If, after cooling, it is discovered
70 by microscopic examination or otherwise,
that the germs still have vitality, the material
is again placed *in vacuo*, and a quantity of
nitrogen gas is introduced in any suitable
manner, so as to fill the germ material. After
75 being kept in this condition for about nine
hours and being subjected to a number of
successions so as to bring the germ mass in
contact with the nitrogen, the latter is re-
moved from the germs which occupy about
80 one-third of the vial, and the air withdrawn
from the same, and the germs again subjected
to a series of successions. Air is now allowed
to enter the vial and the germ material is di-
85 luted with distilled water, alcohol or any other
suitable fluid, to any desired proportion, pref-
erably one part of germ matter to nine parts
of alcohol, when it is poured into a suitable
vessel or jar provided with a valve for attach-
90 ment of an air pump thereto. The said ves-
sel being about one-third full of germ matter,
has the air withdrawn from it, and the mate-
rial therein is subjected to a number of suc-
cussions. Air is now allowed to enter the ves-
sel and fill the vacuum. The germ material
95 is again diluted with alcohol or any other
suitable fluids, and is treated in like man-
ner, as at the preceding dilution. By thus
diluting and succussing, the germ matter be-
comes attenuated until it is of the desired
100 strength for administration without produc-
ing the bad effects heretofore observed. The

germ material is now filtered and sealed in glass stoppered bottles, which are varnished to protect the contents from the rays of light.

The process herein described is equally applicable for preparing medicines in which the molecules are separated by succussion, the succussion *in vacuo* depriving the germ material of air and separating the molecules so as to aid capillary absorption by the blood vessels. The germ or germ material prepared as described, may be used internally or externally, by vaccination, injection, or as a spray.

By having the germ matter placed in *vacuo* before succussion, the air cells are dilated, and are more easily broken or severed. The air and its impurities are removed, thus affording the best condition for succussing or agitating as the liquid strikes the vessel without a cushion. Particles held in solution or suspension are more finely divided and sub-divided, and thereby increase and aid capillary absorption by the blood vessels. It makes a more uniform mixture and improves the keeping qualities of articles *in vacuo*. In many cases it requires less material or medicine to produce the desired therapeutic effects, as the absorption is more readily accomplished by the capillary vessels when cells or particles are finely divided and sub-divided.

Having thus described my invention, what I claim as new, and desire to secure by Letters Patent, is—

1. The process of preparing medicinal substances, consisting in first placing the said substance *in vacuo*, and then subjecting it 35 when in the same to a number of succussions, substantially as described.

2. The process of preparing germ matter for medicinal use, consisting in first placing the same *in vacuo*, and while therein subjecting the same to succussions, then removing and diluting it, and again subjecting it in *vacuo* to succussion, substantially as described.

3. The process of preparing germ matter 45 for medicinal use, consisting in first placing the same *in vacuo*, and while therein subjecting it to succussions, then admitting air and diluting the said matter, heating it and subjecting it to further succussions, substantially 50 as described.

4. The process of preparing germ matter for medicinal use, consisting in first placing the same *in vacuo*, then subjecting it to a series of succussions, then repeatedly diluting 55 it in air and subjecting it to succussions in *vacuo*, next introducing a vitality-destroying gas or substance into the mass so treated, and then subjecting it to succussions as before, substantially as described.

JOSEPH R. WITZEL.
